UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

TWISTING-MACHINE.

1,355,852.

Specification of Letters Patent. Patented Oct. 19, 1920.

Application filed May 15, 1919. Serial No. 297,301.

To all whom it may concern:

Be it known that I, EPPA H. RYON, a citizen of the United States, residing at Waltham, in the county of Middlesex and State 5 of Massachusetts, have invented a new and useful Twisting-Machine, of which the following is a specification.

This invention relates to a twisting machine especially designed for twisting heavy 10 material such as the material from which cocoa mats are woven.

This material is stiff and very bulky and has presented certain difficulties to successful twisting operations. Some of these difficulties arise from the inertia of the heavy 15 spools on which the material is delivered to the machine. It is an important object of my invention to provide a machine in which the axis of the spool is disposed perpendicularly to the axis of the rotatable frame in which the spools are mounted, so that the spools will not revolve relative to the frame from their own inertia after the frame has come to rest.

Other features of my invention relate to improved devices for detachably securing a spool in the rotatable frame, and to improved means for guiding the material to be twisted as it advances from the spool to the point where it is delivered to the winding 20 roll.

My invention further relates to arrangements and combinations of parts, which will be hereinafter described, and more particularly pointed out in the appended claims.

A preferred form of my invention is shown in the drawings, in which—

Figure 1 is a side elevation of my improved twisting machine;

Figs. 2, 3 and 4 are transverse sectional views of the rotatable frame, taken along the lines 2—2, 3—3, and 4—4 of Fig. 1;

Fig. 5 is a sectional detail of one of the bearings of the rotatable frame, and

Fig. 6 is a detailed view of one of the devices for detachably securing a spool in the frame.

Referring to the drawings I have shown a rotatable frame 10 comprising heads 11 and 12, connected by a plurality of tie rods 13, which rods in turn support a plurality of circular disks 14. The frame 10 is sup-

ported in bearings 15 and 16 and is provided with tight and loose pulleys 17 and 18 for the driving belt 19, controlled by a 55 shipper 20.

An additional tight pulley 21, is connected by a belt 22, countershaft 23, and belt 24, to drive a winding roll 25 engaged by a presser roll 26, and rotated in definite 60 speed relation to the rotation of the rotatable frame 10.

Each disk 14 is provided with a stud 27 fixed therein and with a lever 28 pivoted thereto at 29 and supporting a second stud 30. The studs 27 and 30 coöperate to rotatably support a spool S in the central recess of said disk. The shaft upon which the lever 28 is pivoted is extended laterally as shown in Fig. 6 and is provided with a 70 thumb-nut 31, and spring 32, the spring tending to hold the stud 30 in operative position. By this means the spool S is supported with its axis disposed perpendicularly to the axis of the frame 10 and there is, therefore, no tendency for the spool to overrun the frame when the latter comes to rest.

Oppositely disposed guide openings 33 and 34 are provided in the disks 14 through 80 which the material is led from each spool S to the head 12. This head is provided with a plurality of openings 35, preferably corresponding in number to the number of spools mounted in the frame 10, and uniformly spaced about the circumference of the head.

The bearing 16 of the frame 10 is provided with a plurality of guide openings 36, two of which are shown in Fig. 5. These 90 openings 36 converge to a single axial discharge opening 37 from which the material is led to the winding and presser rolls 25 and 26 (Fig. 5).

An intermediate support 38 may be provided, having a plurality of rolls 39 engaging the cylindrical surface of one of the disks 14.

Having thus described my invention it is thought that the operation thereof will be 100 clearly apparent. The coarse yarn or other material is led from the spools S through the guide-openings 33 and 34 to the head 12, where the different strands of yarn are sepa-

rated and pass through the openings 35 to the openings 36 in the bearing 16, and thence to the central discharge passage 37 through which they pass to the winding rolls.

5 When a spool becomes empty it is readily removed from the frame by raising the stud 30 by use of the lever 28, and a fresh spool may be inserted with equal ease.

Having thus described my invention, it 10 will be evident that changes and modifications may be made therein by those skilled in the art without departing from the spirit and scope thereof as set forth in the claims, and I do not wish to be otherwise limited to 15 the details herein disclosed, but what I claim is:—

1. A twisting machine having, in combination, a rotatable frame supported for axial delivery of the twisted material, a plurality of recessed disks supported in said frame and each provided with a slot, a spool mounted in the recess of each disk and disposed transversely of the axis of rotation of said frame, and means to detachably secure 25 each spool to its disk, said means comprising a stud fixed in the disk, a lever mounted in the slot in the disk and having a coöperating stud therein, and a spring to yieldingly advance said lever and stud to holding position.

2. In a twisting machine, a rotatable frame supported for axial delivery of the twisted material, said frame comprising a pair of heads, tie rods connecting said heads, 35 a plurality of circular recessed disks mount-

ed on said rods, and means to support a spool in the recess of each disk with its axis perpendicular to the axis of said frame.

3. In a twisting machine, a rotatable frame supported for axial delivery of the 40 twisted material, said frame comprising a pair of heads, tie rods connecting said heads, a plurality of circular recessed disks mounted on said rods, and means to support a spool in the recess of each disk with its axis 45 perpendicular to the axis of said frame, said disks having oppositely disposed guide openings through which the material to be twisted is drawn direct from a spool; and one of said heads having a number of guide 50 openings equal to the number of spools and through which the material is delivered to an axial discharge passage formed in a bearing portion of said frame.

4. In a twisting machine, a rotatable 55 frame supported for axial delivery of the twisted material, said frame comprising a pair of heads, tie rods connecting said heads, a plurality of circular recessed disks mounted on said rods, and means to support a spool in each disk with its axis perpendicular to the axis of said frame, a portion of 60 each disk being slotted and having a spring-pressed lever mounted therein, said lever having a stud coöperating with a second 65 stud in said disk to support a spool therein.

In testimony whereof I have hereunto affixed my signature.

EPPA H. RYON.
